MICRORAY TUBE AND FREQUENCY
STABILIZING SYSTEMWilliam D. Hershberger, Fort Monmouth,
Oceanport, N. J.

Application July 30, 1936, Serial No. 93,462

11 Claims. (Cl. 250—36)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to micro-ray or ultra high frequency signaling systems and to an electron discharge device for use in such a system.

More particularly the invention proposes a device of this character for generating or producing 10 electrical oscillations of ultra short wave length.

An important object is to produce a tube having a high degree of efficiency as an oscillator or generator of micro-waves when operated in accordance with the Barkhausen-Kurz principle, in 15 which connection the structure, arrangement and function of the electrodes constitute an important part in determining the frequency of the oscillations.

The invention also contemplates an improved 20 transmission circuit and system of frequency stabilization for operation with such a tube.

Other objects and advantages will appear as the description proceeds.

The invention will now be described with reference to the accompanying drawing, in which:

Fig. 1 is a sectional view of a micro-ray tube constructed in accordance with the invention, taken along the longitudinal axis of its electrodes;

30 Fig. 2 is a sectional view taken transversely along the axis of the electrodes; and

Fig. 3 is a diagrammatic view of a tube and suitable transmission line for operation therewith.

35 In the tube here shown by way of example, the numeral 1 designates an envelope of glass or other suitable material, which encompasses a highly evacuated chamber in which the electrode system is disposed. The electrode system comprises a filament or cathode 2, here shown as a straight filament supported upon lead wires 3 and 4, and at one end a suitable spring element 5 is provided to keep the filament under tension and prevent sagging. In practice the filament under tension determines a straight line which may be regarded as coincident with the axis of the tube. Disposed concentrically about the filament as an axis is a helical grid 6, and concentric therewith a multiple plate electrode is provided, which is here shown as comprising three sections 7, 8 and 9. The grid 6 is connected to and supported by outgoing leads 10 and 11 for external circuit connection. The sections 7, 8 and 9 of said plate electrode are connected to

leads 12, 13 and 14, respectively, which are also suitably extended through the envelope for external circuit connection.

Under operating conditions, it has been found highly desirable to be able to place different D. C. potentials on the three sections of the plate electrode. This constitutes an important advantage of the present invention. In practice the two end sections of the plate are usually held at one potential and the inner section is held at a different potential. However, it is possible to generate 23.5 centimeter oscillations holding all plate sections at the same D. C. potential, say for example 20 volts. By making the central or inner plate section 120 volts negative with respect to 15 filament, the power output of the tube increases by a factor of four. Such an adjustment is not possible where the plate electrode is a unitary structure.

The ability to hold the various sections of the 20 three section plate electrode at desired potential differences with respect to filament, and hence with respect to each other, has been found very valuable in making possible the generation of any wave length in a desired range. In operating a 25 tube constructed in accordance with the invention, it was possible to go to the higher frequencies by holding the central plate section slightly negative with respect to filament, and then holding the outside plate sections at a still higher 30 negative potential difference with respect to filament. It is possible with this tube to generate any wave length between such ranges as from 50 to 60 centimeters by changes in the plate voltage. Thus, a decided superiority over prior art devices 35 is secured in affording a flexible control of wave length.

Fig. 3 is a diagrammatic showing of a circuit system in which a tube in accordance with the invention is connected in operative relation. As 40 there shown, it will be noted that the tube is used with a four wire tuned transmission line, one pair of wires 15 and 16 being connected to the helical grid, and the second pair 17 and 18 being connected to the end sections 7 and 9 of the plate 45 electrode. Bars or connections 19 and 20 short circuit said plate and grid lines, respectively. Plate and grid voltages are brought in as at 21 and 22, located at mid-point of said bars. Varying the length of the grid transmission line has a first order effect on the power output of the tube. Lines may be coupled by being placed close together and parallel with one another. Satisfactory operating conditions for obtaining 50 55

maximum power output from the tube are given by way of example, as follows:

5 $E_g = +200$ volts, $I_g = 80$ milliamperes,
 $I_f = 3.2$ amperes, E_p (inner) = -125 volts, and
 E_p (outer) = -20 volts

The end sections of the plate electrode are permitted to undergo certain potential variations and the extent of these variations is subject to adjustment by varying the length of the plate transmission line. For example, in order to obtain the maximum amount of power from the tube over a range of frequencies, it has been found advantageous to adjust the length of the plate 10 transmission line so that it is an integral number of half wave lengths plus or minus a small distance—usually less than 1.0 centimeter. In certain prior art devices where the plate is one cylindrical piece of metal and extends the full 15 length of the grid, it is of necessity an equipotential surface in relation to the grid. A material advantage in favor of the present invention arises from the fact that the outer or end sections of the multiple plate electrode may be caused to 20 undergo potential variations subject to control, thereby increasing the power output of the tube over a relatively wide frequency range.

At this point, it appears desirable to discuss the theory of operation of this tube, which is 25 designed for use as an oscillator in the Barkhausen-Kurz as opposed to the conventional connection. In the conventional connection, the plate is held positive with respect to filament, the grid is usually held negative with respect to 30 filament, the voltage on the grid, i. e., the alternating component of voltage on the grid is 180° out of phase with the voltage on the plate, both plate and grid are equi-potential electrodes, and frequency of oscillation is determined by the 35 inductance and capacity of the associated circuit. In the Barkhausen-Kurz connection the grid is held highly positive with respect to filament, the plate is usually held slightly negative with respect to filament, the grid and plate may 40 or may not be equipotential electrodes as the case may be, and frequency of oscillation is determined in part by tube geometry, i. e., radius of grid and plate, in part by the D. C. voltages impressed on the electrodes, and in part by the 45 constants of an associated circuit, usually a section of transmission line. For certain tubes of this type, the frequency generated is approximately that of an electron oscillating in the inter-electrode spaces back and forth through 50 the meshes of the grid, being attracted by the positive grid and repelled by the negative filament and plate. The mass of the electrons and the electric forces to which they are subjected together determine frequency. In the special 55 tube with which we are here concerned, the grid itself is a resonating element and supports a radio-frequency difference of potential along the direction of its length at the particular frequency at which the grid helix is tuned by virtue of its own distributed capacity and inductance. This 60 arrangement gives substantially two tubes in one envelope in which the elements may be regarded as isolated from each other electrically by the grid helix. As fully herein disclosed, the tube 65 of the present invention proposes a three sectional plate electrode rather than a one or two sectional plate. As previously explained, it is possible to hold the central plate section highly negative with respect to filament, thus confining the oscillating electrons to the ends of the grid.

Output power is increased by a factor of four by adjusting the voltage on the inner plate section from minus 20 volts—where it equals that on the outer plate sections—to minus 120 volts. Since the central portion of the grid is at a voltage 5 node, electrons in this portion of the tube contribute little or nothing to the maintenance of oscillations.

Further, in order to generate oscillation energy of maximum power, it is necessary that the outer 10 plate sections—where the action is localized—be connected together by an impedance as low as can be realized. This is accomplished in the present invention by making this essential connection through a transmission line one-half 15 wave length long and shorted at its far end. Moreover, it has been found that a low impedance path from one end to the other of the plate is one condition to be met for generating oscillations of maximum amplitude. In the present invention, this condition is satisfied for one wave 20 length, namely, that for which the transmission line is one-half wave length long. This gives the tube of the present invention a high degree of wave length stability independent of applied 25 voltages. In the instance of this invention, the section of transmission line is an essential link in the oscillating system and at the same time is a highly tuned filter.

In a tube constructed and operated in accordance with the present invention, the path for radio-frequency currents may be traced as follows: from one end-plate section, through the plate transmission line to the second end plate section, through the electron stream to the portion of the grid nearest the second end-plate section, through the grid transmission line to the remaining end portion of the grid and back through the electrode stream to the first end-plate section. The function of the resonating 35 grid in combination with the highly negative central plate section is to isolate one end of the tube from the other. In the ideal case, the transmission lines furnish the only path for current from one end of the grid to the other, or from 40 one end of the plate to the other. Due to the filter properties of the lines, such a path is furnished at but one frequency.

Changes, modifications and alternative arrangements are contemplated within the scope 50 of the invention as defined by the appended claims.

I claim:

1. In a discharge tube for producing high frequency oscillations, an electrode system comprising a cathode, a grid and an anode, the grid and anode being disposed concentrically about the cathode as a longitudinal axis, and said anode being divided into at least three electrically separated sections; means including said electrode system for producing oscillations, and means for impressing different biasing potentials upon said different sections whereby said oscillations are stabilized.

2. In an electric discharge device for producing micro-wave oscillations, an electrode system comprising a cathode, a grid and an anode, the grid and anode being concentrically disposed about the cathode as an axis, and said anode being divided into a central section and end sections; means including said electrode system for producing oscillations, and means for impressing different biasing potentials upon said different sections, said grid being adapted to oscillate at 75

- the frequency of said oscillations, whereby said oscillations are stabilized.
3. In a discharge tube for producing high frequency oscillations, an electrode system comprising a cathode, a grid and an anode, the grid and anode being disposed concentrically about the cathode as a longitudinal axis, and said anode being divided transversely into at least three electrically separated sections; means including 5 said electrode system for producing oscillations, and means for impressing different biasing potentials upon said different sections whereby said oscillations are stabilized.
4. In a discharge tube for producing high frequency oscillations, an electrode system comprising a cathode, a grid and an anode, the grid and anode being disposed concentrically about the cathode as a longitudinal axis, and said anode being divided transversely into at least three electrically separated sections; means including said 10 electrode system for producing oscillations, and means for impressing different biasing potentials upon said different sections whereby said oscillations are stabilized.
5. In a system for generating high frequency oscillations, a space discharge tube having an electrode system, comprising a cathode, a resonating grid, and an anode divided transversely thereof into a central section and end sections, 15 said sections being electrically separated from one another; means for maintaining the said central section at a difference of potential with respect to the said end sections such as to produce oscillations in said electrode system; a tuned transmission line connected to the free ends of said grid; and means for varying the electrical wave length of said line with respect to the desired operating frequency.
6. In a micro-wave generating system of the character described, a micro-wave tube having an electrode system, comprising a cathode, a resonating grid, and an anode divided transversely thereof into at least three electrically separated sections; a tuned transmission line connected 20 across the end sections of said anode; and means for varying the voltage differential of the two end sections of said anode with respect to the central section for the purpose of stabilizing the frequency output of the system.
7. In a system for generating high frequency oscillations, a micro-wave tube having an electrode system including a cathode, a resonating grid and an anode, said anode being divided transversely thereof into a central section and two end sections all electrically insulated from 25 one another; separate transmission lines connected across the end sections of said anode and the free ends of said grids, respectively; and means including a voltage source for varying the voltage differential of the end sections with respect to the central section, all of said sections being held negative relative to said cathode.
8. In a system for generating high frequency oscillations, a micro-wave tube having an electrode system, including a cathode, a resonating grid, and an anode, said anode being divided transversely thereof into a central section and two end sections all electrically insulated from 30 one another; a tuned transmission circuit operatively connected to said electrode system; means in said circuit including sources of voltage for maintaining different polarizing potentials upon said grid and said anode with respect to the cathode, the said central section and said end sections of the anode being held at negative potential with respect to the cathode and at varying voltage levels with respect to each other whereby said end sections are electrically isolated from 35 one another.
9. In a system for generating high frequency oscillations, a space discharge tube comprising an evacuated container and an electrode system therein, including a cathode, a resonating grid and a cylindrical plate, the grid and plate being disposed about the cathode as a longitudinal axis, and said plate being divided transversely into a central section and end sections electrically insulated from one another; a transmission circuit 40 operatively coupling the electrode system, and including a pair of transmission lines connecting said end sections of the plate electrode; a pair of grid transmission lines connected to the terminals of the grid electrode; shorting bars connecting the ends of said plate and grid transmission lines, respectively; means in said circuit including voltage sources for maintaining different polarizing potentials upon said grid and said plate electrode, plate and grid voltages being applied at midpoints of said plate and grid shorting bars, respectively, the said central section and said end sections of the plate being held at negative potential with respect to the cathode and at varying voltage levels with respect to each other.
10. In an electron discharge device of the character described, an electrode system comprising a cathode, a resonating grid being held at positive potential with respect to the cathode, and an anode, said anode being divided into at least three electrically separated sections, and means for impressing different electrical potentials thereon, one of said sections being held at a negative potential relatively high with respect to said cathode.
11. In a micro-wave tube, an electrode system comprising a cathode, a resonating grid held at positive potential with respect to the cathode, and a multiple anode divided into electrically separated sections; and means for varying and controlling the voltage differential of said sections, including a voltage source for impressing a potential highly negative relative to the cathode upon one section, while impressing a lower value of negative potential with respect to the cathode 50 upon others of said sections.

WILLIAM D. HERSHBERGER.
